UNITED STATES PATENT OFFICE

HARRY H. BURTON, OF WEBSTER, MASSACHUSETTS, ASSIGNOR TO CROMPTON & KNOWLES LOOM WORKS, OF WORCESTER, MASSACHUSETTS, A CORPORATION OF MASSACHUSETTS

THREAD HOLDER FOR WEFT REPLENISHING LOOMS

Application filed March 22, 1932. Serial No. 600,461.

This invention relates to improvements in weft end controllers for weft replenishing looms and it is the general object of the invention to provide means for preventing reverse movements which would permit the thread ends to become slack.

In one form of thread holder adapted more particularly though not necessarily to multicolor weft replenishing looms there are provided travelling surfaces which have frictional engagement with the weft ends extending from the reserve bobbins. A vibration motor is provided to drive these friction surfaces in such a direction as to keep the threads taut. In the construction of the motor there is a pawl to co-act with a ratchet, vibration of the loom operating through a weighted mass to give the pawl working strokes. If the pawl, which in some instances is made in the form of a light leaf spring, is moved from its normal position to a position on the opposite side of a line joining the axis of the rotary ratchet and a point adjacent the anchorage of the pawl on the weighted mass the ratchet together with the travelling friction surfaces will move in the opposite direction and therefore slacken the weft ends, defeating the purpose for which the mechanism is devised. In certain other instances the pawl when thrown to its improper position will lock the travelling surfaces so that they are not free to perform their proper functions.

It is an important object of my present invention to provide means which will prevent the actuating pawl from moving to a position which will permit it to produce retrograde movements of the friction surfaces, or lock the same against vibration induced movements. This result may be accomplished by the use of a stop so placed as to prevent the pawl from moving across the aforesaid line. This stop in some instances can be made adjustable so as to vary the working stroke of the pawl, although this is not an essential feature of the invention. In other instances a check or hold pawl can be employed so proportioned and mounted that it will act to prevent retrograde movements of the actuating ratchet despite the vibration

of the device as a whole during loom operation.

With these and other objects in view which will appear as the description proceeds, my invention resides in the combination and arrangement of parts hereinafter described and set forth in the claims.

In the accompanying drawing, wherein a convenient embodiment of my invention is set forth,

Fig. 1 is a front elevation of a portion of the loom having applied thereto the form of thread holder to which my invention relates,

Fig. 2 is an end elevation on an enlarged scale taken in the direction of arrow 2, Fig. 1,

Fig. 3 is a horizontal section on line 3-3 of Fig. 2,

Fig. 4 is an end elevation taken in the direction of arrow 4, Fig. 3, with the cover removed and showing the preferred form of my invention, and

Fig. 5 is a view similar to Fig. 4 but showing a modification of my invention.

Referring to Fig. 1, I have shown a loom frame 10 and a magazine 11 preferably of the multicolor type provided with reserve bobbins 12 from which extend the weft ends W. The tie rod 13 forming a part of the magazine has secured thereto an arm 14 which projects outwardly and downwardly as seen in Fig. 1.

A foot 15 on the arm 14 supports a casing or box 16. A weight 17 is mounted in the box on the bottom of two upwardly extending springs or resilient supports 18 which are in turn supported by nuts 19 to the frame of the box. As shown in Fig. 4 a pawl 20 may extend from the left hand end of the weight toward the right hand end to have engagement with a ratchet wheel 21 mounted on a shaft 22. The latter has a bearing 23 formed as part of the casing and has secured to the outer end thereof a thread tensioner 24 toothed as shown in Fig. 2.

The tensioner 24 meshes with the teeth of a second tensioning member 25 mounted on an adjustably positioned shaft 26. The shaft 26 extends through a bearing 27 separate from the casing and extending through a horizontal slot 28, and the horizontal posi-

tion of the bearing member 27 can be adjusted by means of screws 29 which extend through slots 30 in the bearing and are threaded into the box.

5 The toothed members 24 and 25 are mounted to rotate freely so that a comparatively slight force is needed to turn them, and they are so geared and related to the weight 17 that their meshing teeth move down in the 10 direction of arrow A, Fig. 2.

During the normal operation of the loom the arm 14 vibrates due to the jarring of the loom and imparts a reciprocating movement to the weight 17. A stop screw 31 may be 15 employed to limit the amplitude of movement of the weight and therefore the working stroke of the pawl 20. The latter meshes with the teeth of the ratchet and as the weight moves to the right as viewed in Fig. 4 the 20 ratchet will be given a slight rotary movement. While the members 24 and 25 must be free to respond to the vibrational force of the weight 17, yet they are sufficiently resistive to retrograde movement to retain the 25 position they occupy when the pawl 20 is at the end of its working stroke. This can be accomplished by the fit of the shafts in their bearings or by means of a friction plate 32 interposed between the box 16 and the 30 left hand faces of the members 24 and 25 as shown in Fig. 3. During continued operation of the loom the toothed members are rotated in opposite directions as suggested by the arrow A in Fig. 2 to exert a downward 35 pull on the threads W.

The matter thus far described of itself forms no part of my present invention and may be substantially the same as shown in prior applications bearing Ser. Nos. 478,429 40 and 569,586 to which reference may be had for a fuller understanding of the construction and operation of the mechanism.

In carrying the preferred form of my invention into effect I provide an extension 50 having a finger 51 which is positioned preferably adjacent the ratchet 21 and as shown in Fig. 4 over the ratchet engaging end of the pawl 20. The finger is so positioned as to permit free working strokes of the pawl 55 but is positioned to prevent the working end of the pawl from moving above a line joining the axis of shaft 22 and the left hand end of the pawl adjacent the point where the latter is secured to the weight 17, thus giving assurance that the ratchet together with the members 24 and 25 will always rotate in the proper direction. Sometimes in clearing the thread holders of undesired threads or in drawing down the weft ends so that they will 60 be sufficiently taut the operator will turn one or the other of the toothed members 24 or 25 by hand and if an attempt should be made to turn these members in the wrong direction the finger 51 will act as an effective stop for the pawl and prevent such move-

ment. It will be observed from Fig. 4 that the pawl is always in contact with the ratchet and that any movement of the ratchet in a clockwise direction will serve only to make tighter the holding connection between the 70 pawl and the ratchet.

In the modification shown in Fig. 5 the structure is retained substantially as used heretofore, except that instead of the finger 51 there is provided a pawl 60 which is an 75 extension of the resilient hanger 61 for the weight 17. The nut 62 holds the resilient hanger in place and also positions the restraining end of the stop pawl 60. A lug 63 rigid with the box 16 prevents buckling of the 80 spring pawl so that the latter is always operative to prevent retrograde movement of the ratchet 21 even though the pawl 20 should move to the dotted line position shown in Fig. 5. 85

From the foregoing it will be seen that I have provided a simple means to prevent the pawl from assuming such a relation with respect to the ratchet as will result in retrograde movement of the members 24 and 25. 90

In the preferred form any such retrograde movement will ultimately move the operating end of the pawl against the finger 51, after which further retrograde movement will be prevented, whereas in the modified 95 form the pawl 60 operates to prevent retrograde movement of the ratchet even though the driving pawl should become improperly positioned. It is to be understood that the form shown in Fig. 5 is but one of several 100 forms of stop ratchets which may be used, but as shown herein as part of one of the resilient supports for the actuating weight. It is to be understood that a slight amount of 105 retrograde movement can properly take place in both forms of the invention, but what I aim to prevent is a substantial retrograde movement which would have the effect of turning the geared members 24 and 25 sufficiently to move the weft ends W in a reverse direction. 110

Having thus described my invention it will be seen that changes and modifications may be made therein by those skilled in the art without departing from the spirit and scope 115 of the invention and I do not wish to be limited to the details herein disclosed, but what I claim is:

1. In a loom thread holder having a travelling thread engaging surface and a vibrating mass, a ratchet operatively connected to the travelling surface, a pawl carried by the vibrating mass to engage the ratchet and means to prevent the pawl from giving the ratchet a substantial retrograde movement. 120

2. In a loom thread holder having a travelling thread engaging surface and a vibrating mass, a ratchet operatively connected to the travelling surface, a pawl moving with the vibrating mass and effective under nor- 130

mal operation to give the ratchet a direct feeding movement, and means to prevent said pawl from giving the ratchet a substantial retrograde movement.

- 5 3. In a loom thread holder having a travelling thread engaging surface and a vibrating mass, a ratchet operatively connected to the travelling surface, a feeding pawl effective normally to move the ratchet in a direct
10 movement, a stop pawl to engage the ratchet and prevent retrograde movement thereof, the first named pawl effective to give the ratchet a direct movement.
4. In a loom thread holder having a pair
15 of coacting thread engaging elements, a bearing member for one of said elements capable of movement to locate said elements at different distances from each other, a vibrating weighted mass, a ratchet movable with one
20 of said elements, a pawl movable by the vibrating mass to engage the ratchet and effective to give the latter a direct feeding movement, and means carried by the bearing to limit movement of the pawl in one direction
25 and thereby prevent the pawl from giving the ratchet a retrograde movement.

In testimony whereof I have hereunto affixed my signature.

HARRY H. BURTON.
